UNITED STATES PATENT OFFICE.

RAYMOND H. KEEVAN, OF CLEVELAND, OHIO.

AUTOMATICALLY-ACTING WASTE APPLIANCE FOR A LAVATORY.

1,183,568.

Specification of Letters Patent.

Patented May 16, 1916.

Application filed September 30, 1914. Serial No. 864,235.

To all whom it may concern:

Be it known that I, RAYMOND H. KEEVAN, a citizen of the United States, and resident of Cleveland, in the county of Cuyahoga and State of Ohio, have invented certain new and useful Improvements in an Automatically-Acting Waste Appliance, for a Lavatory, of which I hereby declare the following to be a full, clear, and exact description, such as will enable others skilled in the art to which it appertains to make and use the same.

The invention relates to improvements in waste appliances for lavatories and the particular feature of the improvement has reference to an automatically acting waste appliance which will act by gravity to discharge the water in the lavatory when the water accumulates therein beyond a predetermined level.

Further features are to provide self cleansing passages for the waste water, and the omission of the overflow passage, and thereby to simplify the construction of the lavatory basin, and to increase the efficiency and utility thereof, and also to provide the same with a seal which will prevent the escape of gas therethrough.

The invention further comprises appliances for retaining the water in the basin under air pressure, until a sufficient weight thereof has accumulated to overcome the air pressure, when the waste will automatically free itself and pass out of the basin.

The invention includes a water seal chamber, an exterior air chamber communicating therewith, and outlet openings in the air chamber through which the waste passes when the air pressure is overcome.

It also includes means for retaining the air in the air chamber while under pressure.

The invention further comprises the combination and arrangement of parts and construction of details hereinafter described, shown in the accompanying drawings and specifically pointed out in the claims.

In the accompanying drawings Figure 1 is a vertical transverse section of the lavatory basin and automatically acting waste appliance and seal and trap. Fig. 2 is an enlarged section of the waste appliance

showing the connections with the waste pipe and air chamber and sealing cup.

In these views A is the basin, B is the outlet nozzle leading therefrom which discharges into a sealing cup C communicating by means of the outlet pipe D with the trap E which discharges into the sewer connections (not shown).

F is a plug which closes the opening leading from the sealing cup C into the outlet pipe D. This plug is raised manually to drain the basin and to admit air after each operation and permit the waste to flow into the trap E by means of a hand pull J, rod K and rock arm L and rod M connected with the plug F. The operating means for the valve including the rod K, rock arm L and rod M, are always submerged in the trap E and hence the air chamber C is always perfectly air tight until waste is discharged or fresh air is admitted after each operation.

At G is shown an air chamber the walls of which inclose the sealing cup and outlet opening leading from the basin A. Openings H, H, in the pipe D permit the waste water to flow out of the air chamber when the air pressure is overcome. The level of the waste fluid remaining in the trap E should preferably be high enough to cover the openings H, H, in the outlet pipe and preserve the air in the air chamber until the pressure is overcome by the weight of waste fluid in the basin.

The operation of the device is as follows: The manual operation when it is desired to empty the basin is simple and has already been described to consist merely in lifting the plug by means of the hand lift. The automatic action takes place when the user does not lift the plug but permits the waste water to accumulate in the basin, then the water flows into the sealing cup and overflows into the air chamber. The seal of the cup prevents the escape of the air meanwhile until the waste fluid has attained a predetermined level in the basin, then the weight of the fluid will overcome the pressure of the air confined in the air chamber and also the weight of the fluid in the trap and will escape through the openings H, H, in the outlet pipe. The fluid in the trap

will always prevent the escape of sewer gas into the basin and the seal formed in the cup and the outlet nozzle from the basin will prevent the upward escape of the air 5 from the air chamber when under pressure.

It is obvious that the waste can be discharged wholly by means of the automatic air pressure controlled method, but a manual control is added to insure complete 10 drainage of the sealing cup.

The outlet tube D leading from the cup is smaller in diameter than the diameter of the trap, and is preferably attached thereto by means of a screw thread so as to be adjustable therein. The cup is raised above 15 the bottom of the chamber G and the level of the water in the basin is controlled by means of the level of the upper edge of the cup. In adjusting the cup the openings 20 H, H, must not be covered up.

Having described the invention what I claim as new and desire to secure by Letters Patent is:

1. The combination with a basin having 25 an outlet nozzle, of means for automatically controlling the discharge of fluid from said basin, said means comprising an air confining chamber arranged to receive said outlet nozzle and communicating with the exterior atmosphere only by way of said nozzle, said chamber having a valveless drainage outlet near the bottom thereof, a waste pipe connected with said drainage outlet, said waste pipe being provided with a liquid 30 seal, a sealing cup within said air chamber and arranged to receive the basin outlet nozzle, the wall of said sealing cup extending above the drainage outlet of the air chamber and having the rim thereof spaced 35 from the top of said air chamber and manually operated means for draining said sealing cup.

2. The combination with a basin having an outlet nozzle of means for automatically 45 controlling the discharge of fluid from said basin, said means comprising an air confining chamber arranged to receive said outlet nozzle and communicating with the exterior atmosphere only by way of said nozzle, said chamber having a valveless drainage outlet near the bottom thereof, a waste pipe connected with said drainage outlet, said waste pipe being provided with a liquid 50 seal, a sealing cup within said air chamber and arranged to receive the basin outlet nozzle, the wall of said sealing cup extending 55 above the drainage outlet of the air chamber and having the rim thereof spaced from the top of said air chamber, said sealing cup being provided with a drainage outlet in its bottom, a plug for closing said drainage outlet and manually operated means for shifting said plug.

3. The combination with a basin having

an outlet nozzle, of means for automatically 65 discharging fluid accumulated in said basin, said means comprising an air confining chamber arranged to receive the outlet nozzle, said chamber communicating with the exterior atmosphere only by way of said 70 nozzle, said chamber having a drainage outlet, a waste pipe connected with said drainage outlet, said waste pipe being provided with a liquid seal, and vertically adjustable means for sealing said air chamber for preventing 75 the escape of air therefrom by way of the basin outlet, said adjustable sealing means comprising a cup arranged to receive the lower portion of the basin outlet, said cup having a drainage opening connected 80 with the drainage opening from said air chamber, and a valve arranged to close said opening and manually operated means for opening and closing said valve.

4. The combination with a basin having 85 an outlet, of means for automatically discharging fluid accumulated in said basin, comprising, an air confining chamber, an outlet nozzle, extending from the outlet of the basin into said chamber, a sealing cup 90 in said chamber and arranged to receive the end of the outer nozzle, said cup raised above the bottom of said air confining chamber, an outlet pipe supporting said cup upon the bottom wall of said chamber and provided 95 with perforations intermediate of said cup and bottom wall of said chamber, a valve in said outlet pipe, controlling the opening leading to said outlet pipe, an exterior trap communicating with said outlet pipe, and 100 means for operating said valve, said means submerged within said trap.

5. The combination with a basin having an outlet, of means for automatically discharging fluid accumulated in said basin, including, an air confining chamber communicating with said outlet from said basin, said air confining chamber having a separate outlet and vertically adjustable means for sealing said air chamber to prevent the 110 escape of air therefrom by way of the basin outlet, said adjustable sealing means controlling the attainable water level in said basin.

6. The combination with a basin having 115 an outlet nozzle, of means for automatically controlling the discharge of fluid from said basin, said means comprising an air confining chamber arranged to receive said outlet nozzle and communicating with the exterior atmosphere only by way of said nozzle, said chamber having a valveless drainage outlet near the bottom thereof, a waste pipe connected with said drainage outlet, said waste pipe being provided with a liquid 120 seal, a sealing cup within said air chamber and arranged to receive the basin outlet nozzle, the wall of the sealing cup extending 125

above the drainage outlet of the air chamber and having the rim thereof spaced from the top of said air chamber, said sealing cup being provided with a drainage outlet in its bottom, a plug for closing said drainage outlet, means for shifting said plug arranged entirely within the waste pipe and a rod for actuating said means, the lower end of said rod being operatively connected with

said means at a point below the normal level 10 of the liquid seal in said waste pipe.

In testimony whereof, I hereunto set my hand this 18 day of Sept., 1914.

RAYMOND H. KEEVAN.

In presence of—

Wm. J. KLOTZBACH,
Wm. M. MAURVE.
